UNITED STATES PATENT OFFICE.

JOHN K. OLSEN, OF CHICAGO, ILLINOIS, ASSIGNOR TO STEWART-WARNER SPEEDOMETER CORPORATION, OF CHICAGO, ILLINOIS, A CORPORATION OF VIRGINIA.

ODOMETER.

Application filed December 27, 1921. Serial No. 524,895.

To all whom it may concern:

Be it known that I, JOHN K. OLSEN, a citizen of the United States, residing in the city of Chicago, in the county of Cook and State of Illinois, have invented certain new and useful Improvements in Odometers, of which the following is a specification, reference being had to the accompanying drawings, forming a part thereof.

10 The purpose of this invention is to provide an improved construction of a counter train, particularly of the type of an odometer, that is, having the counter wheels graduated in terms of distance of travel, of a vehicle to be served by the instrument, which shall be simpler and more compact in construction than similar devices heretofore employed. It consists in the elements and features of construction shown and described, as indicated 20 in the claims.

In the drawings:

Figure 1 is a partly sectional plan view of a structure embodying this invention with the casing cover removed and the dial wheels partly broken away and shown in section, section being made at the horizontal axial plane of the dial wheels.

Figure 2 is a detail section at the line, 2—2, on Figure 1.

30 Figure 3 is a detail section at the line, 3—3, on Figure 1.

Figure 4 is a horizontal axial section showing a modification in certain details.

35 Figure 5 is a section at the line, 5—5, on Figure 4.

Figure 6 is a section at the line, 6—6, on Figure 1.

In the structure shown in the drawings, there is a frame or support A comprising 40 end bearing members, A¹ and A², and an intermediate bearing, A³, for the drive gear hereinafter mentioned. In the bearings, A¹ and A², there is mounted for rotation and limited longitudinal movement, a main central shaft B for which the journal bearing

45 is provided in the left hand standard, A¹, by means of an intruded bushing, a¹, adapted, by being screwed in, to be adjusted within a limited range, and secured as adjusted by

50 a nut, a¹⁰. The end of the shaft which is journaled in this bushing is axially bored at b for the housing of a spring, F, which reacts between the shaft and the bushing for yieldingly holding the shaft thrust to the

right to a limit which is determined by the 55 encounter with a bushing, a², of the shoulder, b⁵, formed on the shaft toward the right hand end by the reduction in diameter of said right hand end portion of the shaft as shown at B¹. On the shaft, B, there is mounted loosely a drive gear, C, which is journaled in the bearing, A³, above mentioned, which thereby constitutes substantially a journal bearing for the shaft as well. The drive gear, C, is adapted to be driven in any suitable manner by or from the shaft whose revolutions are to be counted or indicated. The driving means illustrated is one most familiar, consisting of a worm gear, C¹, on an inleading shaft, c¹, for which a journal bearing member a⁴, is provided projecting from the back wall, A⁴, of the support, A. On the shaft, B, at the right hand side of the drive gear, C, there are mounted the numeral 60 wheels or dials of the odometer trip train, graduated as usual, decimally, the initial right hand dial being graduated to indicate tenths of a mile, the next numeral wheel being the units wheel, and the third at the left the tens wheel. Between said tens wheel, D³, 65 and the drive gear, C, there is disposed a disk spring, K, for taking up the slack of the trip train and holding the several members thereof in snug relation to each other. At the left hand side of the drive gear, C, there are shown 70 in succession, three blinds or dummy dials, E, e¹ and e²,—that is, wheels might be but are not graduated so as to constitute dials. Next, following these dummy wheels at the left are five numeral wheels or dials held in snug 75 assemblage with the wheels, E, e¹ and e² by the adjustment of the journal bushing, a¹, as described. Familiar means of carrying from wheel to wheel are provided for both the trip train and the total travel train, as 80 indicated at the meeting planes of the consecutive wheels by the carrying pinions, G, on the counter-shaft, g, journaled in the frame uprights, A¹, A² and A³.

85 The initial or lowest-denomination wheel, D¹, of the trip train is engaged with the shaft, B, for rotation by means of either a spline or inwardly projecting pin, d¹⁰, on the wheel engaging a longitudinal groove, b¹⁰, in the shaft, as seen in Fig. 1, a spline or projecting pin, b¹, on the shaft, B, engaging a longitudinal groove, d¹, in said wheel, D¹, as seen in Fig. 4. Similarly, the 90

corresponding wheel, E, of the total travel train is engaged with said shaft, B, either by an inwardly projecting pin, e, on the wheel engaging any one of ten longitudinal 5 grooves, b⁴⁰, on the shaft as seen in Fig. 1, or by means of a spline or projecting pin, b⁴, on the shaft entering one of ten longitudinal grooves, e⁴⁰, in said wheel, E. In addition to the longitudinal or paraxial 10 grooves, b⁴⁰, or e⁴⁰, there is provided a circumferential groove, b⁵⁰, in the shaft (see Fig. 1) or e⁴, in the wheel (see Fig. 4), positioned offset from the plane of rotation of the spline or pin, e or b⁴, at the normal position 15 of the shaft, B, a distance equal to the thrust of the shaft from its normal position to the limit determined by the clearance provided by the depth of the bore in the journal bushing, a¹, so that when the shaft is thrust into that limit, the spline or pin, e or b⁴, being in the groove, b⁵ or e⁴, the shaft rotates without rotating the numeral wheel, E, and therefore, of course, without operating any of the remainder of 20 the total travel train.

The dummy or numeral-less wheels, e¹ and e², are both loose on the shaft; the wheel, e¹ is rigid for rotation with the drive wheel, C, and said dummy wheels, e¹ and e², and 25 the wheel, E—(which is also usually without rotation indicating markings, although to be regarded as the lowest-denomination wheel of the total travel train because having the same rotation as the lowest denomination wheel, D¹, of the trip train), together 30 with the carrying means connecting them successively, constitute a speed reducing train by which the speed derived by the wheel, E, from the drive wheel, C, is reduced 35 to 1/100th of that of said drive wheel.

The right hand end of the shaft, B, is provided with an operating knob, B⁴. The operation of the structure described may be understood to be, that in the ordinary operation,—that is, when driven by the wheel 45 whose speed is to be indicated,—rotary motion is first transmitted through said gear, C, wheels, e¹, e², and their respective carrying means to the wheel, E, which by the 50 spline-and-groove engagement described, rotates the shaft, B. Said shaft, B, in turn by the spline-and-groove engagement described rotates the lowest-denomination wheel of the trip train, D¹; and from said 55 wheels, E and D¹, respectively, proper rotation is communicated by the carrying devices to the successive wheels of the trip train and total travel train, respectively. For re-setting, the operator will push inward 60 on the knob, B⁴, thrusting the shaft, B, to the inward limit, causing the disengagement of said shaft from the gear, E, but not effecting the engagement of the shaft with the gear, D¹. While holding the shaft 65 thus thrust inward it may be rotated in

either direction for setting the trip train either forward or backward to any desired point without effecting the total travel train.

When the construction having the pins in the wheels and the grooves in the shaft is adopted, as shown in Fig. 1, the wheels which are to carry the pins are made with a central bushing, X, which has the pin formed by striking a punch radially inward part way through the radial thickness of the bushing, forcing the metal out as an interior projection, as seen in Figure 1.

I claim:—

1. A revolution counter comprising in combination two trains of numeral wheels and a unitary shaft on which both of said trains are carried; means for rotating said shaft from the shaft whose revolutions are to be counted, bearings in which said shaft is mounted for longitudinal movement to a determined limit in one direction, and between which the numeral wheels are held against such movement; a spring which yieldingly holds the shaft to the other limit; the lowest denomination wheel of each train having spline-and-groove engagement with the shaft for rotation therewith, adapted to permit relative movement of the shaft and wheel longitudinally of the shaft; the grooved element at the shaft engagement of the lowest denomination wheel of one of the trains having also a circumferential groove for engagement of the spline to permit relative rotation of said shaft and wheel, said grooves and splines being positioned in the respective parts for the first mentioned engagement at normal position of the shaft and for the second engagement at said determined limit of the shaft away from normal position.

2. A revolution counter comprising in combination with a frame structure, a main central integral shaft supported in said frame; a decimal series of counter wheels, all carried side by side on said shaft; a gear on said shaft, and driving connections independent of the rotation of said shaft from said gear to the lowest denomination wheel of the counter train, and to said central shaft; means for driving said gear meshing directly therewith; said central shaft being longitudinally movable in said frame and disengageable from said driving connection by such movement, and means for holding the counter wheels against lateral displacement in such movement of said shaft.

3. In combination with the construction described in claim 2 foregoing, a second decimal series of counter wheels, all carried side by side on said shaft, the lowest denomination wheel of said second train being directly engaged with said shaft for rotation therewith throughout the longitudinal adjustment of said shaft, and means for holding the wheels of said second counter

train against lateral displacement in said longitudinal movement of the shaft.

4. In the construction defined in claim 2, foregoing, means for holding the first mentioned gear against displacement from position for meshing with its driving means in the longitudinal movement of the shaft.

5. In the construction defined in claim 1, foregoing, the grooved element at the engagement of the lowest-denomination wheel of the train for which the shaft has the circumferential groove mentioned having ten circumferentially equal spaced longitudinal grooves.

15 6. An odometer and the like comprising a supporting frame structure and a shaft journaled therein, a train of counter wheels mounted side by side on said shaft; a gear

on said shaft and connections by which it drives the train of counter wheels and said shaft; an inleading power shaft journaled in the frame structure having gear means meshing directly with the first mentioned gear for driving the same, the first mentioned shaft being longitudinally movable 20 in its bearings through the first mentioned gear thereon for disconnecting said shaft from its driving connections with said gear, and means for preventing the disengagement of said gear from the gear on the inleading shaft in said longitudinal movement of the shaft.

In testimony whereof, I have hereunto set my hand at Chicago, Illinois, this 20 day of December, 1921.

JOHN K. OLSEN.
